COMBUSTION CHAMBER

Earl W. Jorolemon, Rochester, N. Y., assignor to
 General Motors Corporation, Detroit, Mich., a
 corporation of Delaware

Application July 1, 1940, Serial No. 343,336

5 Claims. (Cl. 158—4)

This invention relates generally to improvements in the construction of water heaters which are particularly adapted for use with fluid fuel burners.

The principal object of the invention is to provide a universal type of water heater which is highly efficient in operation and relatively low in cost and which is especially suitable for either large domestic hot water supply systems or small steam or hot water heating systems.

One of the principal features of the invention is the construction of the combustion chamber, which is preferably of relatively thin sheet metal, for use with a conventional gun or pressure atomizing type of burner, to provide a relatively confined space to promote combustion and afford an efficient radiant heat transfer to the heat-absorbing walls of the water heater.

A further feature of the invention resides in the provision of a vertical sheet metal target and baffle plate within the combustion chamber between a horizontal side opening for the burner tube and an outlet opening adjacent the bottom of the combustion chamber.

A further feature of the invention is the provision of a baffle between the combustion chamber and outlet flue which causes a more intimate contact between the combustion gases and the heat-absorbing walls of the water heater.

Other objects and features of the invention, such as the location and mounting of the combustion chamber and the burner in the water heater and the novel arrangement, construction and combination of parts together with the advantages thereof, will be apparent from, or specifically pointed out in the following description and accompanying drawings in which:

Fig. 1 is a vertical sectional view, with parts in elevation, of a water heater or boiler embodying my invention.

Fig. 2 is a fragmentary front elevation showing the burner mounting plate and adjacent parts with the burner removed.

Fig. 3 is an enlarged fragmentary section taken substantially on line 3—3 of Fig. 2.

Fig. 4 is an enlarged perspective view of the combustion chamber with the upper section detached to show the interior construction.

Fig. 5 is an enlarged fragmentary perspective view of a modification of the securing means for the combustion chamber.

Referring first to the showing in Fig. 1, the water tank comprises the outer tank shell 2 consisting of the vertical cylindrical portion 4 and an upper end 6 and lower end 8 welded thereto

and supported and secured as by means such as brackets 10, on a base ring 12. The water tank is preferably enclosed by the casing or jacket 14 and the space between the tank and jacket is preferably filled with insulating material such as rock-wool which may be blown under pressure into this space.

Within the outer shell 2 of the water tank is an inner combustion shell 16 consisting of the vertical cylindrical portion 18 and the upper end 20 and lower end 22 welded thereto. This inner shell 16 is spaced from the outer shell both at the sides and top and bottom to form therewith a water containing space which completely encloses the inner shell 16 except adjacent the flue passage and burner mounting as will be hereinafter described. The walls of this inner shell 16 furthermore provide or define the combustion space 24.

The upper ends 6 and 20 of shells 2 and 16, respectively, are provided with vertically aligned openings to receive the flue pipe 26 which is welded to such ends and serves to connect the combustion space 24 to the stack or smoke pipe 28. Adjacent its lower end the shell 2 is provided with a drain valve 30 and a water return or inlet 32 and the upper end 6 of shell 2 is provided with the hot water or steam outlet pipe 34.

A water temperature control unit 36 and stack mounted burner control unit 38, may be located as shown in Fig. 1. Such controls do not comprise a part of my invention and may be of any conventional type. It should also be understood that, depending upon the desired function and operation of the complete unit as either a domestic water heater or a steam or hot water boiler, certain other conventional controls would be employed such as a water temperature limit control, a steam pressure control and a pressure relief valve, together with any desired indicating gages such as a pressure gage and water level column. As an added safety precaution a fusible plug 40 has been shown as located between the water space and combustion space.

Referring now to the combustion apparatus, the shells 2 and 16 are provided with aligned openings to receive a generally elliptical sleeve 42 which is welded to the shells and serves to support the burner and combustion chamber and provide an opening or passage into the combustion shell 16. It will be here noted that except for the space occupied by the sleeve 42 and the flue pipe 26, the combustion shell 16 is entirely surrounded by the water space between the shell 16 and tank shell 2 and a portion at least of the

flue pipe 26 is also surrounded by the water space to thereby provide an efficient heat exchange.

The outer end of the sleeve 42 is adapted to be substantially entirely closed by the burner mounting plate 44 secured to the sleeve as by hook bolts 46 extending around the inner end of the sleeve as shown in detail in Fig. 3 and a suitable gasket or packing 48 may be provided between the plate 44 and the outer end of sleeve 42. The mounting plate 44 is provided with a suitable opening to receive the burner tube 50 of the oil burner indicated generally at 52 which may be secured to such plate as by bolts 54. The oil burner 52 has not been shown in detail but it will be understood that the same is generally of the pressure atomizing type in which liquid fuel is discharged under pressure through an atomizing nozzle in the burner tube 50 and adapted to mix with air supplied through such tube to form the combustible mixture.

The fuel mixture issuing from the burner nozzle and tube 50 is projected into the sheet metal combustion chamber indicated generally at 56 in which practically complete combustion occurs before the combustion gases escape into the combustion shell 16. The chamber 56 is made of relatively thin sheet metal of such material as certain chrome steel alloys which have been found to withstand the high temperatures encountered and attain a maximum temperature and become practically incandescent almost immediately upon starting the burner to transmit radiant heat directly to the walls of the combustion shell 16 from which the heat is efficiently absorbed by the water surrounding such shell.

As shown generally in Fig. 1 and in detail in Fig. 4, the combustion chamber 56 may be readily constructed with a cylindrical body portion 58 and substantially conical upper and lower end portions 60 and 62, respectively. The lower end portion 62 is preferably welded to the body portion 58 and such parts may be inserted as a unit into the combustion space 24 through the opening provided by the sleeve 42. Such opening is not sufficiently large, however, to permit of the insertion of the complete combustion chamber and to facilitate the assembly thereof within the combustion space, the upper end portion 60 is provided with spaced openings or slots 64 adapted to receive the upwardly extending clips 66 on portion 58 which may be bent over the periphery of the upper end portion to secure the same in position.

The cylindrical body portion 58 of the combustion chamber is provided at one side with a circular inlet opening and with an external cylindrical sleeve 68 secured thereto at such opening which is adapted to fit around the burner tube 50 and provided with spaced projecting tongues 70 which are adapted to be bent outwardly as shown in Fig. 2 and clamped with a suitable gasket 72 between a flange 74 on the burner tube 50 and an offset portion of the mounting plate 44. As shown in Fig. 4, the tongues 70 may be formed as extensions on angle brackets which connect the sleeve 68 to the combustion chamber portion 58, or as shown in Fig. 5, the tongues indicated at 76 may be separately formed and welded to the sleeve 68 independently of the angle brackets 78 which connect the sleeve to the chamber portion 58. The combustion chamber 56 is adapted to be primarily supported by this connection to the mounting plate 44 but to properly position the same within the combustion shell 16 and also support the same to some ex-

tent, the cylindrical portion 18 of the shell may have welded thereto spaced inwardly extending brackets such as indicated in Fig. 1 at 80 which are inclined or have an inclined surface to engage the conical lower end portion 62 of the combustion chamber.

Both the upper and lower end portions of the combustion chamber 56 are closed except for a relatively restricted outlet opening indicated at 82 in Fig. 1 in the lower end portion 62 adjacent the side opposite the burner inlet opening. As shown in Figs. 1 and 4, a transverse, sheet metal target and baffle plate 84 is provided within the combustion chamber intermediate the inlet and outlet openings and preferably closely adjacent the latter. This plate 84 extends vertically into the path of some of the fuel mixture from the burner and is preferably made of special heat-resisting chrome steel to withstand the intense heat to which the same is subjected. To stiffen the plate against permanent distortion it is formed with a top flange 86 and to permit repeated expansion and contraction on heating and cooling without buckling, it is preferably secured within the combustion chamber only adjacent each end as by angle brackets 88 welded to the body portion 58 and to the ends of the plate, and the lower edge of the plate may be slightly spaced from the adjacent wall of the lower end portion 62.

The combustion chamber 56 provides a relatively confined space in which practically complete combustion occurs before the combustion gases or products of combustion escape through the relatively restricted outlet 82 into the combustion space 24. However, it is preferable that the relative dimensions of the chamber 56, the location and dimensions of the target and baffle plate 84 therein, and the dimensions of the outlet 82 be such that this desirable result is attained without any appreciable resistance to the escape of the combustion gases or the development of any appreciable combustion pressure within the chamber 56.

The plate 84 has been referred to heretofore as a target and baffle plate. As will be apparent, such plate is positioned partly in the path of some of the fuel mixture from the burner to function as a target and not only thereby provide for increased turbulence of the burning mixture but also attain an extremely high temperature and assist in the vaporization of any unatomized oil from the burner nozzle. The plate 84 also functions as a baffle to prevent the fuel mixture or burner flame from passing directly to the outlet 82 and by thus increasing the length of flame travel within the chamber 56, it tends to retain the burner flame in the chamber 56 until complete combustion of the fuel mixture therein. In actual practice it has been found that very little, if any, flame ever issues from the outlet 82 and the entire chamber 56 reaches a state of incandescence within a period of less than two minutes from the time when the burner is started from a cold condition.

As has been mentioned, the combustion shell 16 will, therefore, be primarily heated by direct radiation from the chamber 56. The shell 16 is also, of course, heated to some extent by the combustion gases escaping from the combustion chamber downwardly through the outlet 82. Such gases are discharged downwardly into the combustion space 24 into contact with the lower end of the shell 16 and then pass upwardly in the space 24 around the combustion chamber 56 to

the flue pipe 26 where further heat is extracted by the water or steam surrounding a portion of such pipe.

To cause the combustion gases to pass in more intimate contact with the heat absorbing surfaces of the combustion shell 16 adjacent the connection thereof to the flue pipe 26, a substantially dome shaped baffle 90 is preferably suspended as by a transverse rod 92 directly beneath the lower end of the flue pipe 26. As will be readily apparent from the showing thereof in Fig. 1, this baffle 90 intercepts the direct passage of combustion gases from the central portion of the combustion space into the flue pipe and permits the gases to enter the flue pipe only after passing around the baffle through the relatively restricted space between the baffle and the adjacent side and upper walls of the combustion shell 16. As is indicated in Fig. 1 the baffle 90 preferably consists of a circular head 94 and depending cylindrical skirt 96 with an open bottom to thereby cause eddy currents in the combustion gases to reduce the velocity thereof and also absorb some heat from the gases and radiate the same to the adjacent heat absorbing surfaces of the shell 16.

It has been found desirable under certain conditions of combustion to admit a small quantity of secondary air to the combustion space 24 to prevent a condition known in the art as "puffing." For this purpose the burner mounting plate 44 is provided with an inspection opening adapted to be normally substantially closed by a hinged door 98 which is spaced however from the plate 44 as shown in Fig. 1 at 100 to provide for communication between the combustion space 24 and the atmosphere. As will be understood this inspection door 98 is provided to permit examination, when desired, of combustion conditions within the combustion space 24 and the character of the combustion gases therein.

It will be apparent that many changes and modifications may be made in the detailed construction and arrangement of parts within the scope of my invention and that many advantages of the several novel features thereof in addition to those mentioned herein will be obvious to those skilled in the art.

I claim:

1. In a heating apparatus, a heat exchange unit including heat absorbing and transmitting walls defining a hollow combustion space, a combustion chamber within said space having top, bottom and side walls, said combustion chamber having an inlet opening in the side wall thereof at one side of said chamber and an outlet opening in the bottom wall adjacent the side opposite said inlet opening, a liquid fuel burner associated with said inlet opening, and a baffle member in

said combustion chamber between said inlet and outlet openings.

2. In a heating apparatus, a heat exchange unit including heat absorbing and transmitting walls defining a hollow combustion space, a combustion chamber within said space having top, bottom and side walls, said combustion chamber having an inlet opening in the side wall thereof at one side of said chamber and an outlet opening in the bottom wall adjacent the side opposite said inlet opening, a liquid fuel burner associated with said inlet opening, and a baffle member in said combustion chamber between said inlet and outlet openings having a portion thereof located in the direct path of a portion of the fuel mixture from said burner.

3. In a heating apparatus, a heat exchange unit including heat absorbing and transmitting walls defining a hollow combustion space, a combustion chamber within said space having top, bottom and side walls, said combustion chamber having an inlet opening in the side wall thereof at one side of said chamber and an outlet opening in the bottom wall adjacent the side opposite said inlet opening, a liquid fuel burner associated with said inlet opening, a baffle member extending transversely within said combustion chamber between said inlet and outlet openings, and means to rigidly secure said baffle member adjacent its ends to said combustion chamber adapted to provide for expansion and contraction of said member intermediate the ends thereof on changes of temperature.

4. In a heating apparatus, a heat exchange unit including heat absorbing and transmitting walls defining a hollow combustion space, a combustion chamber within said space having top, bottom and side walls, said combustion chamber having an inlet opening in the side wall thereof at one side of said chamber and an outlet opening in the bottom wall adjacent the side opposite said inlet opening, a liquid fuel burner associated with said inlet opening, and a baffle member in said chamber between said inlet and outlet openings and providing compartments therein which communicate only adjacent the upper part of said chamber.

5. In a heating apparatus, a heat exchange unit including heat absorbing and transmitting walls defining a hollow combustion space, and a combustion chamber within said space comprising a substantially frusto-conical closed upper end portion, an intermediate substantially cylindrical portion having an inlet opening in one side adapted to receive a burner tube, and a substantially frusto-conical lower end portion having an outlet opening into said combustion space adjacent the side opposite said inlet opening.

EARL W. JOROLEMON.
